(57) **CLAIM**

What is claimed is the ornamental design for a base for control panel for a construction machine, as shown and described.

DESCRIPTION

FIG. 1 is a top front perspective view of the base for control panel for a construction machine. The broken lines showing a plug protruding from the front of the article are shown for

environmental purposes only and form no part of the claimed design. The broken lines in the center of the Figure are shown to define a boundary around a portion of the article which is not part of the claimed design. The area within the broken line boundary is not part of the claimed design.

FIG. 2 is a top plan view of the base for control panel for a construction machine of FIG. 1. The broken lines showing a plug protruding from the front of the article are shown for environmental purposes only and form no part of the claimed design. The broken lines in the center of the Figure are shown to define a boundary around a portion of the article which is not part of the claimed design. The area within the broken line boundary is not part of the claimed design.

FIG. 3 is a bottom view of the base for control panel for a construction machine of FIG. 1. The broken lines showing a plug protruding from the front of the article are shown for environmental purposes only and form no part of the claimed design. The broken lines in the center of the Figure are shown to define a boundary around a portion of the article which is not part of the claimed design. The area within the broken line boundary is not part of the claimed design.

FIG. 4 is a rear side elevation view of the base for control panel for a construction machine of FIG. 1.

FIG. 5 is a front side elevation view of the base for control panel for a construction machine of FIG. 1. The broken lines showing a plug protruding from the front of the article are shown for environmental purposes only and form no part of the claimed design.

FIG. 6 is a left end elevation view of the base for control panel for a construction machine of FIG. 1. The broken lines showing a plug protruding from the front of the article are shown for environmental purposes only and form no part of the claimed design; and,

FIG. 7 is a right end elevation view of the base for control panel for a construction machine of FIG. 1. The broken lines showing a plug protruding from the front of the article are shown for environmental purposes only and form no part of the claimed design.
